UNITED STATES PATENT OFFICE.

ERD V. CROWELL, OF TULSA, OKLAHOMA.

OIL-WELL-CASING CEMENTING SHOE.

Original application filed June 15, 1920, Serial No. 389,151. Divided and this application filed March 9, 1921. Serial No. 451,032.

To all whom it may concern:

Be it known that I, ERD V. CROWELL, a citizen of the United States, and a resident of Tulsa, in the county of Tulsa and State of Oklahoma, have invented certain new and useful Improvements in Oil-Well-Casing Cementing Shoes, of which the following is a specification.

My invention relates to improvements in well casings, particularly those of the type employed in oil and gas wells, and it consists in the constructions, combinations and arrangements herein described and claimed.

One of the foremost objects of the invention is to provide a cementing shoe for use in connection with an oil or gas well casing, by means of which a cementing mixture, as for example mud-fluid, can be ejected from the lowermost section or "oil string" to fill the space between the "oil string" and well bore and thus seal the formation seat against the seepage of water.

A further object of the invention is to provide a cementing shoe for oil or gas well casings, which offers the distinctive and exclusive advantage of providing means for placing a cementing mixture behind the "oil string" while the well is expelling oil and gas and the casing is resting on its formation seat.

A further object of the invention is to provide means for introducing a cementing mixture into the space between the "oil string" and wall of the hole, without having to first plug the hole beneath the casing, raise the casing or work against the high pressure of the oil and gas.

A further object of the invention is to provide means in oil or gas well constructions, enabling the making of a water-tight seal between the casing and rock formation independently of the casing shoe on the lowermost extremity of the "oil string" or the texture of the landing formation on which the shoe rests.

A further and important object of the invention is to provide means, including a valve mechanism forming part of the well casing, enabling placing a mud-fluid or other cementing mixture behind the "oil string" while it is resting on its formation seat, and oil and gas are being expelled through the casing.

Other objects of my invention will ap-

pear in the following specification, reference being had to the accompanying drawings, in which:—

Figure 1 is a longitudinal section illustrating the casing cementing shoe and its associated parts in the operative position in the "oil string" of a well casing, said casing being shown resting on its formation seat near the bottom of the bore.

Figure 2 is a detail sectional view illustrating the mudding packer in the approximate position to have the upper and lower packer rubbers expanded against the cementing shoe.

Figure 3 is a similar view, taken at right angles to the section in Figure 2, illustrating the mudding packer in the operative position opposite the mud valves in the cementing shoe.

Figure 4 is a detail side elevation of the mudding packer before the rubbers are expanded, the supporting slips at the bottom being shown disassembled for purposes of illustration.

Figure 5 is a detail longitudinal section of the cementing shoe with its mud valves,

Figure 6 is a detail horizontal section on the line 6—6 of Figure 5, showing how the mud valves are mounted,

Figure 7 is a detail plan view of the rubber-expanding spider, and

Figure 8 is a detail horizontal section taken substantially on the line 8—8 of Figure 4, and showing the springs and associated parts of the supporting slips.

This is a division of my co-pending application for Letters Patent for oil well casing cementing shoes, filed June 15, 1920, Serial No. 389,151.

In order that the reader might be able to more fully appreciate the purpose of the invention, it is thought well to preface the description of the construction and mode of operation by a brief description of the oil and gas well casing operation. Casing, as now used in oil field operation, in either iron or steel tubular pipe, the kinds and sizes thereof differing considerably in the various fields, all according to the peculiar conditions encountered. The process of lowering a string of casing into the bore of an oil or gas well, and allowing it to rest on a formation seat, as shown in Figure 1, is commonly referred to as "landing" the casing.

A complete column of pipe or casing as placed in the bore of oil wells, is commonly referred to as the "string" of casing. The fundamental purpose of the oil well casing 5 is that of protection, that is to say, to keep the water and other foreign substances from falling into the shot hole at the bottom and thereby either crowding the oil back from the bore or obstructing the lower end of the 10 bore in such a manner that neither oil nor gas can flow.

The problem of water exclusion from oil wells is merely that of inserting a string of water-tight casing, so that its bottom is 15 tightly lodged below the lowest water-bearing stratum and above the top of the productive oil sand, thereby sealing the water off from descent below the casing, thus preventing water originating above from invading the productive oil or gas sands below.

In drilling oil or gas wells, the formations passed through as the depth increases consist of alternating layers of lime-stone, shale, and occasionally a stratum of sand. The 25 shale layers predominate over the lime layers as regards number and thickness, and again the lime layers predominate over the sand layers in the same manner. Usually the underground water finds its channels of flow 30 in the lime or sand strata, the water flowing through the sand stratum generally above or below a lime stratum.

As the depth of the hole is increased during the drilling operation, water producing 35 lime or sand strata are encountered, the water thus released by the puncturing of the strata by the drill point, settling in the hole and filling it with water. The drilling operations are thus greatly retarded, due to 40 the cushioning effect the water has on the drilling operation of the tools.

Again, the water released from the lime strata washes down over the shale strata below, causing the shale to cave, slough out 45 and fall down the hole. A loose shale formation may thus cave to such an extent as to even entirely bury the tools. An enormous amount of additional work is required in thereafter excavating the material and re- 50 covering the tools.

Referring to Figure 1, it is obvious that for the casing to successfully perform its function of protecting the "shot hole", in the productive oil or gas sand, as represented at O, from being flooded with water that originates in the strata above the casing seat S, it is necessary that the casing shoe 2 make a positive water-tight seal or bond with the rock formation at S.

60 When the casing has been "landed" on its formation seat S and the casing shoe 2 has made a positive water-tight seal with the formation seat S, it is said to have made a "shut-off", as commonly referred to. The 65 present day methods of effecting a positive

water-tight seal between the casing shoe 2 and the formation seat S, separate themselves into two main classifications, the "formation shut-off" and the "cement shut-off".

Formation shut-off is the term commonly 70 applied to the operation of excluding water, where the casing, with a shoe of some kind, is landed or driven into a stratum of shale or clay, using no artificial bond. Cement shut-off is the term commonly applied to the 75 operation of excluding water, where cement or mud-fluid is used to form a bond between the casing and the formation in which the shoe of the casing is landed.

Formation conditions, and texture of the 80 landing formation are often such that the casing shoe 2 is prevented from making a seal or bond with the formation seat S. Consequently, water finds its way down around the casing shoe 2, and the casing 1 thus fails 85 in its primary function of protecting the productive oil or gas sand from being flooded with water from above, commonly referred to as "top water".

It is generally conceded by those experienced in the art, that the only means of providing a water-tight bond or seal between the casing and the formation, independent of mechanical packers, is by the application of cement or mud-fluid behind the casing 90 and above the casing shoe 2. It is the prime purpose of the device to provide means of placing cement or mud-fluid behind the casing of oil or gas wells in a way more expeditious than is commonly practiced, and 100 even under conditions that render the application of cement or mud-fluid impossible as ordinarily applied. With this brief survey in mind, the need for the improvement which the invention affords will be understood. Referring now to the generalized form of the invention, in Figures 1 to 8 inclusive, it is to be observed that the "oil string" comprises several casing sections 1, which occupy a substantially central position in the well bore B, the casing shoe 2 at the lowermost extremity resting on an annular projection of rock or other material, commonly known as the formation seat S. The bore of the well merges with the opening 115 O in the stratum of oil or gas sand, commonly known as the shot hole.

The very first consideration is to produce a water-tight joint or bond between the casing shoe 2 and the formation seat S. In 120 order that the need of the invention may be more fully appreciated, and a particular and exclusive advantage more thoroughly understood, it is thought well to explain the method, now practised, of placing a sealing material behind the casing of oil or gas wells.

Therefore, digressing briefly from the description of the invention, it is well to bear in mind that the method, now practised, is to insert or build a temporary plug in the 130

hole beneath the formation seat S, which serves the purpose of a barrier to prevent the sealing material, consisting of cement or mud-fluid, from entering and clogging the productive oil sand O, also to prevent the expelling oil or gas from interfering with the introduction of the sealing material through the casing.

After the temporary plug is thus in place, and the oil and gas effectually sealed in, the sealing material is then introduced through the casing where it falls on top of the plug, when it is necessary to lift the casing from its formation seat so as to let the sealing material out into the annular space between the casing and wall of the bore. After the sealing material has been forced from the casing, with a column of water above, to fill the annular space outside the casing, the casing is again let down, and the temporary plug in the hole drilled out.

Now, due to a heavy internal "sand pressure" and consequent violent expulsion of oil and gas, under heavy pressure, it is often impossible to insert or build a temporary plug beneath the formation seat S, and above the oil or gas sand, as such a procedure requires. Aside from the impossibility of applying a sealing material by this method, in many instances, it offers the disadvantage of having to suspend production for a time. It is also regarded by those experienced in the art, that the question of determining just when the casing is lifted from its formation seat, and just when the cementing material has been forced out of the casing to fill the annular space outside of the casing, offers one of the most perplexing problems in the application of this method, the accurate determination of which is necessary for assurance of its successful operation.

for assurance of its successful operation.

By referring to Figure 1, a particular and exclusive advantage of my invention may be observed, whereby means are provided for 45 the introduction of a sealing material through the tubing 25, while oil and gas is being expelled through the casing 1, exterior of the tubing 25, thus obviating the necessity of having to temporarily plug the well in, 50 or raise and lower the casing.

50 of false and lower the casing.
Reverting now to the description of the invention: There are two major parts of which it is constituted, namely, the cementing shoe 3, and the mud packer 4. The cementing shoe 3 is very much like one of the sections of the well casing, it being in fact, joined to one of them by the coupling 5 in Figure 1. Both ends are threaded; one for the coupling 5 and the other for the bowl 6, which in turn is very much like an ordinary coupling since it has the same external and internal diameters.

Two or more valves 7 normally close ports 8 in the annular enlargement 9 of the shoe 65 3, each being held in place by rather power-

ful arcuate leaf springs 10, which are secured to the shoe at 11. The springs occupy an annular groove 12 and are sheltered therein by the overhanging parts of the enlargement 9. 70

Either the flange 13 or a series of projections in the same place, which would accomplish the same purpose, support the mud packer 4 in the bowl 6 of the cementing shoe, by virtue of the engagement of the slips 14 therewith. These slips are segmental as shown in Figures 4 and 8, having keeper slots 15 shaped to suit the keys 16 on the slip cage 17. Recesses 18 in the slips 14 accommodate springs 19 which force the slips outwardly into contact with the adjacent wall. 75 80

The casing bowl 6 is machined from a steel forging and when thus machined is provided with a tapering portion 20 which aids in contracting the slips 14 when pulling the mud packer 4 out of the casing. The surfaces of the slips 14 are slightly convexed to facilitate the withdrawal of the mud packer. The adjusting ring 21 on the lower end of the shell of the packer 4, abuts the 90 slideable packing mechanism on the shell to lift said mechanism out of the casing upon withdrawing the packer.

95 withdrawing the packer.

The upper threaded end of the packer shell carries the collar 22, into which the spider 23 is screwed, the legs 24 of the spider resting on the collar. The mud tubing 25 is screwed into the spider from above, while the delivery tube 26 is screwed into the spider from beneath. But by virtue of the 100 fact that the delivery tube is integrally joined to the packer shell 4 at the right angled outlet extension 27, it would be more nearly correct to say that the spider 23 is screwed onto the delivery tube 26. 105

There are two packer rubbers on the shell 4; the upper rubber 28 is located below the collar 22, the other rubber 29 below the mud-fluid distributor ring 30. This ring has an annular concavity 31 which readily permits the mud-fluid to flow to all outlet valves 7 from the point of discharge 27. The distributor ring 30 is slidable on the shell 4 and has a slot 32 which enables relative movement of the ring in respect to the outlet 27 without obstructing the outlet. 115

A base ring 33 provides the foundation for the lower packer rubber 29, in that the lower packer rubber employs the base ring as an abutment against which to expand, and in that the base ring holds the lowermost rubber out of the casing bowl 6. It is necessary that the lowermost rubber 29 expands against the shoe 3 slightly below the discharge valve 7, the parts of the mechanism being so proportioned that this action will always occur. 120 12

A bridge ring 34 provides a complete foundation on which the upper packer rubber 28 rests, the bridge ring closing the up- 13

per opening of the slot 32 in the distributor ring 30, as clearly shown in Figure 4. Normally, the mud-fluid outlet 27 is disposed slightly above the zone of the valves 7. This is shown in Figure 2. But as additional tubing sections 25 are screwed in place, the weight upon the spider 23 increases so that the rubbers 28 and 29 are gradually compressed and expanded against the wall of the shoe 3, while the discharge outlet 27 ultimately finds a position in line with the valve 7.

It is important that particular attention be called to valves 7, upon which depend the practical value and possible operation of the invention; it is to be understood, therefore, that modifications and changes as to their particular design and number may be made without departing from the spirit of the invention.

The operation may now be easily followed. As the well drilling operation progresses and various water-bearing strata are encountered, sections of piping are let down. These become progressively smaller as the depth of the well increases, and the uppermost ones are known as "water strings." As mentioned above, the lowermost section of piping is known as the "oil string," and a portion thereof is shown in Figure 1. The casing shoe 2 is solely for the purpose of imparting strength to the oil string and keep it from crimping due to the enormous weight imposed thereon. It is very seldom that a satisfactory joint forms of its own accord between the shoe 2 and the formation seat S. A mud seal meets all requirements satisfactorily.

The cementing shoe 3 is introduced in the casing 1 at the desired location from the bottom, the mud-fluid outlet valves 7 being normally held closed by the leaf springs 10. The tubing 25 with its mud packer mechanism 4 is lowered into the casing, the slips 14 rubbing against the casing walls by virtue of the springs 19 behind them, until they encounter the supporting ledge 13 near the bottom of the casing bowl 6.

It is the weight of the tubing 25 on the spider 23 and associated parts, whereby the upper and lower rubbers 28 and 29 are caused to expand from the positions in Figures 2 and 5 to that shown in Figures 1 and 3. They form a perfect seal between the shell 4 of the packer and the shell 3 of the shoe, the concavity 31 of the mud distributor ring 30 constituting an annular channel which leads the mud fluid to the two or more discharge valves 7.

It is of utmost importance to observe that while mud-fluid is being pumped through the tubing 25, gas and oil are enabled to escape up through the casing but around the tubing. The pressure of the mud fluid opens the valves 7 so that the material flows out

into the space between the casing and the wall of the bore B, filling all crevices and excluding the water which flows from water bearing strata, from the casing of the well. Naturally, none of this water can seep into the shot hole O because of the secure seal around the shoe 2. If desired, mud fluid may be pumped in until it overflows at the top, and when the seal is completed, the mud packer 4 is withdrawn by pulling on the tubing 25.

While the construction and arrangement of the improved casing cementing mechanism as herein described and claimed, is that of a generally preferred form, obviously modifications and changes may be made without departing from the spirit of the invention or the scope of the claims.

I claim:—

1. A well casing resting on its formation seat in a well bore open to a productive stratum, and means forming one of the sections of the casing, including valve mechanism enabling the ejection of sealing material from inside of the casing into the space between the casing and bore, while fluid flows through the casing from said productive stratum.

2. The combination of a well casing, and means located in the casing for conducting sealing material to a point of discharge in the wall of the casing, in a direction opposite to that of the fluid flow in the casing without obstructing it.

3. The combination of a well casing, and its formation seat in a bore opened to a productive stratum, a conduit on the interior of the casing conducting sealing material in the direction opposite to the flow of fluid from the stratum without obstructing said flow, and a valve apparatus embodied as a section of the casing, through which the sealing material from the conduit is ejected into the space between the casing and bore to form a tight joint around the formation seat.

4. The combination of a well casing and its formation seat in a bore opened to a productive stratum—a conduit on the interior of the casing conducting sealing material in the direction opposite to the flow of fluid from the stratum without obstructing said flow, a valve apparatus embodied as a section of the casing, through which the sealing material from the conduit is ejected into the space between the casing and bore, and means for distributing the sealing material for uniform ejection at the members of the valve mechanism.

5. The combination of a well casing, a cementing shoe embodied as one of the casing sections, with a plurality of valved ports; a delivery tube interiorly of the casing for conducting sealing material to said ports; and means operatively associated

- with a part of said tube for securing a tight joint against the casing above and below said ports.
6. The combination of a well casing, a cementing shoe embodied as one of the casing sections, with a plurality of valved ports; a delivery tube interiorly of the casing for conducting sealing material to said ports; means operatively associated with a part of said tube for securing a tight joint against the casing above and below said ports, and means for circumferentially distributing the sealing material to said ports from the discharge of said tube.
- 15 7. The combination of a well casing, a cementing shoe embodied as one of the casing sections, with valved ports; tubing interiorly of the casing conducting sealing material to said ports, including a packer shell spaced from the casing but enabling the passage of fluid through the casing while the sealing material flows in said tubing; and packing means in the space between said shell and casing forming a tight joint above and below said valved ports.
8. The combination of a well casing, a cementing shoe embodied as one of the casing sections, with valved ports; tubing interiorly of the casing conducting sealing material to said ports, including a packer shell spaced from the casing but enabling the passage of fluid through the casing while the sealing material flows in said tubing; packing means in the space between said shell and casing forming a tight joint above and below the valved ports, and a ring surrounding the packer shell and forming an abutment for said packer means, for distributing the sealing material to said ports.
- 40 9. The combination of a well casing, with a cementing shoe having a plurality of valved ports; tubing interiorly of the casing for conducting sealing material to the ports, including a packer shell spaced from the casing and slightly movable relative thereto; a ring surrounding said shell for distributing the sealing material to all ports, including a slot preserving communication of the tubing outlet during said shell movement; a ring bridging the slot at the upper end of the distributor ring, packer means in the space between the shell and casing, abutting the bridge and distributor rings; and means carried by the shell and tubing for expanding the packer means to form a tight joint above and below said valved ports.
10. The combination of a well casing, a cementing shoe coupled in the casing, with a plurality of valved ports; tubing interiorly of the casing conducting sealing material to said ports, including a packer shell capable of slight movement in respect to the casing; packer means on the shell to form a tight joint above and below said ports, and means carried by the shell engageable by a portion of the casing at a predetermined place to constitute an abutment against which said packer means expand.
11. The combination of a well casing, including a cementing shoe with a plurality of valved ports, and a casing bowl with a supporting ledge; tubing inside the casing conducting sealing material to said ports, and including a packer shell capable of slight movement in respect to the casing; normally contracted packer means carried by the shell, for making a tight joint between the shell and casing above and below said ports, and means carried by the shell engageable with said supporting ledge to constitute an abutment against which said packer means expand during said slight movement of the shell.
- 15 12. The combination of a packer shell, with a slip cage; a casing bowl in respect to which the packer shell has slight movement, including a supporting ledge; and slips carried by the cage, with springs for pressing the slips against the wall of the casing bowl thereby to engage the ledge and provide an abutment.
13. The combination of a packer shell, with a slip cage having recesses and keys, a casing bowl in respect to which the packer shell has slight movement, including a supporting ledge; and slips occupying the recesses, with openings receiving the keys for limiting the outward movement of the slips, including springs urging the slips into contact with the bowl wall as the packer shell moves downwardly, said slips finally engaging the ledge to form an abutment.
14. The combination of a cementing shoe, with a series of valved ports, and an attached casing bowl of an internal diameter larger than that of the shoe, including a supporting ledge; and a packer shell spaced from the shoe, with upper and lower packer rubbers in said space, and abutment means engageable with the ledge, against which said rubbers expand to form tight joints.
- 15 15. The combination of a well casing, including a cementing shoe with a series of valved ports; and tubing for conducting sealing material to the ports, with an integral packer shell spaced from the casing and carrying upper and lower packer rubbers, and a spider and collar respectively carried by the tubing and shell, for expanding the rubbers at the sides of the ports by virtue of the weight of the tubing.
16. The combination of a well casing with a fixed abutment and a series of valved ports; tubing in the casing for conducting sealing material to the ports, made integrally with a packer shell spacedly located from the casing; an abutment carried by and movable with the shell into engagement with said fixed abutment, packer rubbers respectively above and below said series of ports.

- 6
- in the space between the shell and casing, and means including a spider, mutually carried by the tubing and shell for imposing the weight of the tubing on the rubbers to 5 expand them into tight engagement with the casing, the lowermost rubber abutting the movable abutment through a base ring.
17. The method of sealing wells, consisting of lowering a well casing into permanent engagement with the formation seat 10 near the bottom of a bore, and introducing

sealing material into the bore around the casing without stopping the flow of fluid through the casing.

18. The method of sealing wells, consisting of lowering a valved well casing into permanent location on the formation seat of a bore, and introducing sealing material into the casing to flow out of the valve and fill the surrounding bore. 15

ERD V. CROWELL.
